STRAND WORKING APPARATUS

Edwin J. McIlvried, Cleveland, Ohio, assignor, by
mesne assignments, to Western Electric Com-
pany, Incorporated, New York, N. Y., a Cor-
poration of New York

Application August 12, 1929. Serial No. 385,171

7 Claims. (Cl. 205—16)

This invention relates to strand working appa-
ratus, and more particularly to wire drawing
apparatus.

It is the usual practice in the drawing of wire,
5 especially in the manufacture of fine wire, to
wind the drawn wires on a take-up spool which
is operated at high speed, resulting in the accu-
mulation of considerable energy in the rotating
10 spool as the amount of wire wound thereon in-
creases. In the operation of the same winding
or spooling apparatus, the momentum of the
spool will oftentimes be sufficient to cause the
15 wire to break, usually between the spool and the
capstan. Loss of time in the operation of the
machine consequently results, for it is necessary
to rethread or restring the machine.

The principal object of the invention is to pro-
vide an efficient strand working apparatus in
which a strand may be wound continuously at
20 high speed.

In accordance with one embodiment, the in-
vention contemplates a high speed wire drawing
machine including the usual drawing drum or
capstan for drawing the wire through reducing
25 dies and a take-up spool on which the drawn
wire is wound. Both the capstan and take-up
spool are driven by power communicated through
a clutch and mechanical brake device. Specifi-
cally the shaft of the take-up spool is equipped
30 with an electromagnetic brake which is con-
trolled by an electrical switch operated by a
manually actuated control mechanism for ren-
dering the clutch ineffective and the mechanical
brake effective, or vice versa. Upon operating
35 the control mechanism to release the clutch to
discontinue the operation of the wire drawing
machine, the electro-magnetic brake is applied
to the take-up spool shaft prior to the opera-
tion of the mechanical brake to stop the capstan
40 shaft. By stopping the take-up spool before
bringing the capstan to a full stop the momen-
tum of the spool is eliminated and thus breakage
of the wire between the capstan and the take-up
spool is prevented.

45 Other features and advantages of the inven-
tion will be apparent from the following descrip-
tion when taken in conjunction with the accom-
panying drawings, in which

50 Fig. 1 is a plan view of a wire drawing machine
with the improvements incorporated therein;

Fig. 2 is a fragmentary elevational view of
the take-up or spooling end of the machine;

Fig. 3 is an enlarged fragmentary vertical sec-
55 tion taken on the line 3—3 of Fig. 1;

Fig. 4 is an enlarged fragmentary vertical sec-
tion also taken on line 3—3 of Fig. 1 and is a
continuation of the left hand end of the struc-
ture shown in Fig. 3, and

60 Fig. 5 is an enlarged vertical section taken on

line 5—5 of Fig. 1 on the shaft for the take-up
spool.

Referring now to the drawings in which like
reference numerals designate similar parts
throughout the various views the wire drawing
65 machine, indicated as a unit by the numeral 1,
is operated by an electric motor 2 driving a main
or worm shaft 3 which drives a worm gear 5
through a worm 6. This shaft 3 as shown in
Fig. 3 is journaled in a bearing 8 and its inner
70 end, terminating at a point centrally of the ma-
chine, has a clutch disk or ring 10 secured there-
to. Positioned within a bearing 15 of the clutch
disk 10 is an end of a capstan shaft 12, which
is supported in bearings 14 in the machine and
75 is provided with a worm 16 for driving a main
capstan 18. It will be understood that the ma-
chine may be equipped for coiling the wire in-
stead of spooling, in which case the shaft 12
drives the block.

80

The right hand bearing 14 (Fig. 3) is sup-
ported in a bracket 19 which is integral with
the frame of the machine and forms a housing
20 surrounding but spaced from the shaft 12.
Between the clutch disk 10 and the housing 20
85 is located a slidable sleeve 21 which is shown
in Fig. 3 in a neutral position, but when moved
to the right, operates and expands a clutch 24
which engages the disk 10 and couples the shafts
3 and 12. When the sleeve is moved in the op-
posite direction, or to the left, it expands a brake
25 against the inner surface of the stationary
housing 20 to stop the rotation of the shaft 12
and thus the rotation of the capstan.

90

The left hand end of the shaft 12 is connected
95 through a coupling 28 to a spooling or take-up
driving shaft 29 which is supported at its outer
end in a sleeve 30 mounted in bearings 31 in
the housing. To the left hand end of the shaft
29 is connected a driving disk 32 (Fig. 4) which
100 is arranged to drive frictionally a casing 35 car-
ried upon and connected to a sleeve 30 provided
with a spiral gear 36. The gear 36 in turn
meshes with a spiral gear 38 (Fig. 5) which is
carried upon and drives a transverse spool shaft
40. This latter shaft is supported in bearings
42 in the frame and at its outer or left hand
end carries a take-up spool 44, driving the spool
through a pin disk 45. On the right hand end
of the shaft 40 (Fig. 5) is mounted a brake drum
46 which is surrounded by a brake 48. This
110 brake is preferably of the electro-magnetic type
operating to hold the brake open or unapplied
when the magnetizing coil thereof is energized,
and upon de-energization to release the brake
so that it can be applied to the drum by springs
incorporated in the brake mechanism. The de-
tails of the brake are not shown and described,
as these are well known in the art, it being suffi-
115 cient to state that any substitute form of brake

105

110

115

120

may be employed, an electro-magnetic type of brake being preferred.

The disk clutch 24 and the brake 48 are designed to be operated by a common actuating means which is preferably intended to be operated so that the brake is applied to the spool shaft just after the release of the clutch and prior to the application of the brake to the capstan. This sequence of operation is desirable in order to bring the spool to a stop before the capstan is stopped, and thereby avoid snapping the wire between the capstan and the spool. The operation just described is performed by a lever 50 which is pivoted on a bracket 52 on the frame of the machine. The lever 50 is connected to a shaft 53 carrying an operating lever 54 which, extended in one direction, engages a groove in the outer face of the sleeve 21 and in the opposite direction is connected to a sliding rod 55 which carries a collar 56, designed to operate a switch 58 controlling the electromagnetic brake.

To bring the machine to a stop the lever 50 is moved in a counter-clockwise direction (Fig. 2) causing the sleeve 21 (Fig. 3) to be moved to its neutral position away from the disc clutch 24, to disengage the clutch 24, and also causing the rod 55 (Fig. 2) to move to the left. Further movement of the lever 50 in a counter-clockwise direction moves the rod 55 further to the left and moves the sleeve 21 out of its neutral position. Since, as is stated above, the common actuating means or lever 50 is adapted to apply the brake 48 to the spool shaft before the brake 25 is applied to the capstan and since the brake 48 is of the electromagnetic type requiring a definite interval of time to be applied after the switch 58 is opened the rod 55 is preferably adjusted to open the switch 58 before the lever 50 has been moved in a counter-clockwise direction sufficient to cause the sleeve 21 to actuate the brake 25.

It is apparent that while the particular forms of brakes on the capstan and spool are preferred, other forms of brakes may be substituted. The essential features of the invention are the provision of separate braking devices for the capstan and the spool together with a common actuating device for applying both brakes at substantially the same time, the take-up spool brake being applied preferably slightly ahead of the capstan brake. This same actuating means also operates the clutch to the capstan shaft.

It will be understood that the embodiment of the invention herein described and illustrated is merely a convenient and useful form of the invention, which is capable of many other modifications without departing from the spirit and scope of the invention as defined by the appended claims.

What is claimed is

1. In a strand working apparatus, a strand advancing means, a strand storage means, means for actuating the strand advancing and the strand storage means, means for connecting and disconnecting the strand advancing and the strand storage means to and from the actuating means, a brake for the strand advancing means, a brake for the strand storage means, and means for first operating the connecting means, then the brake for the strand storage means, and then the brake for the strand advancing means.

2. In a wire drawing apparatus, a driving shaft, a strand advancing drum shaft, a take-up

spool shaft, a clutch between the driving shaft and the drum shaft, a driving connection between the drum shaft and the spool shaft, a brake for the drum shaft, a separate brake for the spool shaft, and a common actuating means for releasing the clutch, applying the brake to the spool shaft, and applying the brake to the drum shaft in the order named. 80

3. In a wire drawing apparatus, a driving shaft, a capstan shaft, a take-up spool shaft, a clutch between the driving shaft and the capstan shaft, friction driving means between the capstan shaft and the spool shaft, a brake for the capstan shaft, a brake for the spool shaft, and a common actuating means for releasing the clutch, applying the brake to the spool shaft, and applying the brake to the capstan shaft in the order named. 85 90

4. In a strand working apparatus, a strand advancing drum, a take-up spool for receiving a strand advanced thereto by the drum, a brake for the drum, a brake for the take-up spool, and movable means for controlling the brake for the take-up spool and for controlling the brake for the drum, connecting means associated with said movable means and said spool brake when said movable controller has reached a predetermined position for applying said spool brake, and other connecting means associated with said movable controller and said drum brake when said movable controller has reached another predetermined position for applying said drum brake. 95 100

5. In a strand working apparatus, a strand advancing means, a strand storage means for receiving a strand advanced thereto by the advancing means, a braking mechanism for the advancing means, a braking mechanism for the strand storage means, a shaft, a lever mounted on the shaft, connecting means associated with said shaft and said storage means brake when said lever has reached a predetermined position for first operating the braking mechanism for the strand storage means and other connecting means associated with said shaft and said advancing means brake when said lever has reached another predetermined position for operating the braking mechanism for the strand advancing means. 110 115 120

6. In a strand working apparatus, a strand advancing means, a strand storage means, means for actuating the strand advancing and strand storage means, a brake for the strand advancing means, a brake for the strand storage means, and a rock-shaft being responsive in predetermined movements for disengaging the actuating means, for applying the brake for the strand storage means, and for applying the brake for the strand advancing means in the order named. 125 130

7. In a strand working apparatus, driving means therefor, a strand advancing means, transmission elements including a shaft and a clutch associated with said driving means and said strand advancing means for actuating said strand advancing means, a take-up spool, other transmission elements including a friction drive associated with said take-up spool and said shaft for actuating said take-up spool, a brake associated with said first mentioned transmission elements on the driven side of said clutch, a second brake associated with said other transmission elements on the driven side of said friction drive, and means for releasing said clutch, applying said second brake and applying said first brake in the order named. 135 140 145
